COMB AND NAIL FILE COMBINATION

William Donald Hooper, Baltimore, Md.

Application November 15, 1948, Serial No. 60,063

2 Claims. (Cl. 132—79)

1

This invention relates to toilet articles and more particularly to combs for use on the hair of individuals and similar purposes.

It has among its objects to provide a new and improved comb that will avoid one or more of the disadvantages and limitations of the prior art.

Another object of the invention is to provide a new and improved comb that will be of a construction suitable for holding incidental parts usable with the requirements of completing the toilet of an individual. A further object of the present invention is to provide a new and improved comb that will facilitate its placement in the pocket or purse of the user and provide other features of convenience to him.

Other objects of the invention will become apparent as the invention is more fully described.

For a clearer understanding of the invention, its objects and principles reference is made to the appended drawings. These drawings in conjunction with the following description outline a selected form of the invention by way of example while the claims emphasize the scope of the invention.

Referring to the drawings:

Figure 1 is a side view of a comb embodying this invention;

Figure 2 is a plan view of the invention;

Figure 3 is a sectional view of the body of the comb taken on line 3—3 of Figure 1;

Figure 4 is a view similar to Figure 1, with the nail file removed.

Similar numerals relate to the same parts of the structure throughout the drawings.

In the particular construction indicated in the drawings, a comb body 10 is formed of plastic or other suitable material commonly employed for the purpose. This comb has its body rounded at the corners 11 at each end of it, and teeth 12 project downwardly from it in tapered contour to the useful edge of the comb and are aligned between the end shoulders 13. The teeth are spaced according to fine or coarse combing in two sections of the comb in a conventional manner. The general details of the comb and its purposes are so well known as to avoid the necessity of requiring explanation thereof. However this particular comb has the following features. First its body 10 is varied in thickness throughout its length to make it thicker in the middle portion 18 and then taper off gradually towards the shoulders 13. The thickened part is termed the "hump" arbitrarily. The body 10 adjacent the shoulders 13 is provided with short closed in slots 14 that are of sufficient depth to receive the handle 15 and point 16 of a conventional flat nail file 17, the file structure being formed on the half of the file leading towards the point. When the file 17 is placed in the slots 14 it is bent by the hump 18 and serves to make it hold itself resiliently therein.

while at the same time being rendered available for grasping by the fingers when the user wants to take it out. The file also indicates to the user, by its position which end of the comb has the coarse teeth and which the fine teeth. This indication is given visually or by the sense of touch.

A comb of this form has a number of features that appeal to many users. It has a structure that facilitates the holding of the manicuring tools in a compact and effective manner and has them always available. This is not only a convenience but also retains the flat nail file commonly used for manicuring purposes where it will not be dangerous. The common objection to the nail file is that it is easily lost and hard to find when dropped. Its flat and sharpened edges are normally so exposed that they can injure a person very readily, as well as cut holes in the pockets, they allow the file as well as other articles in them to become lost readily, and is a source of continual distress. While the file is in position on the back of the comb it reinforces it and makes it stronger.

While but one general form of the invention is shown in the drawings and described in the specifications, it is not desired to limit this application for patent to this particular form or in any other way otherwise than limited by the scope thereof, as it is appreciated that other forms of construction could be made that would use the same principles and come within the scope of the appended claims.

Having thus described the invention, what is claimed is:

1. A comb comprising an elongated back having inturned ends providing terminal pockets, said pockets each having a front wall lying in one plane and a rear wall lying in another plane and said pockets opening toward each other, said back having, medially of its length, a thickened portion on the side of the pockets, the face of which lies in a plane between said two planes, said pockets being adapted to receive the opposite ends of a flexible article extending lengthwise of the comb, while the thickened portion of said comb presses against the article to resiliently hold it in the pockets.

2. A comb as set forth in claim 1, said pockets being so shaped as to conform to each end of the article carried therein.

WILLIAM DONALD HOOPER.
